DERICK

Emmett Lee Alexander, Enid, Okla., assignor to
The George E. Failing Supply Company, Enid,
Okla., a corporation of Oklahoma

Application June 23, 1948, Serial No. 34,800

7 Claims. (Cl. 254—139.1)

1

This invention relates to a derrick or mast adapted for use in connection with portable drilling rigs and particularly suitable for mounting on a truck or similar chassis.

The principal object of the invention is to provide a strong, light-weight construction wherein the loading is substantially equalized on the respective legs of the derrick.

Other objects of the invention are to provide a derrick with a simple and efficient crown block structure which permits a pulley arrangement to promote equalization of loads on the derrick legs and which keeps a wide spread on the tackle cables to maintain stability of the traveling block and prevent twisting of the lines; to provide a crown block for the derrick having a pulley arrangement which permits placement of the sand pulley tangentially with the axis of the hole to be drilled; to provide a crown block having portions overhanging front and rear sides of the derrick; to provide for free action of the tackle cables; and to provide an open face derrick wherein the "crow's nest" or platform at the top of the derrick is utilized as a structural part for supporting and distributing loads acting on the derrick.

It is also an object of the invention to provide the crown block with a simple and efficient cover for enclosing the pulleys and which may be readily moved out of position to facilitate reaving of the tackle cables and inspection of the pulleys and their bearings.

It is also an object of the invention to provide rollers to guide the cables used in effecting make up and breaking of the joints.

In accomplishing these and other objects of the invention, I have provided improved structure, the preferred form of which is illustrated in the accompanying drawings wherein:

Fig. 1 is a perspective view of the lower portion of the mast constructed in accordance with the present invention and showing the mast mounted on the chassis of a motor vehicle.

Fig. 2 is a perspective view of the upper portion of the mast particularly illustrating the crown block and "crow's nest."

Fig. 3 is a vertical section through the upper portion of the mast taken on the line 3—3 of Fig. 2.

Fig. 4 is a vertical section on the line 4—4 of Fig. 2.

Fig. 5 is a plan view of the crown block frame showing the pulley arrangement.

Fig. 6 is a cross section through the derrick particularly illustrating the platform of the "crow's nest."

Referring more in detail to the drawings:

1 designates a derrick constructed in accord-

2

ance with the present invention and which is adapted for mounting on a truck chassis 2. The mast includes front and rear corner legs 3—4 and 5—6 that are preferably formed of tubes. The side legs 3—5 and 4—6 are interconnected along the height thereof by horizontal girts 7 and 8 and diagonal braces 9 and 10. The rear legs 5 and 6 are also interconnected by horizontal girts 11 and intermediate sway braces 12. The legs 10 are spaced apart at the lower end to provide a substantially wide footing for the front legs and the rear legs are pivotally mounted on a bracket 13 which extends transversely across the platform of the chassis and on which the derrick is adapted to pivot from a reclining position for transportation to the erect position shown in the drawing. The bracket structure includes vertical members 14 and 15 connected by a cross member 16. The cross member 16 cooperates with the platform 17 of the chassis to mount vertically positioned laterally spaced rollers 18 for a purpose later described. The front of the derrick, that is, the side as viewed toward the end of the truck chassis is open between the front legs to provide an open faced derrick in which tackle mechanism including a traveling block 19 is adapted to operate so that it is in position over the center of the hole to be drilled when the drilling unit is in operation.

In order to reinforce the derrick and compensate for the open side thereof, horizontal girts at selected levels are interconnected by a truss structure 20 including brace members 21 and 22 connecting central portions of the rear girts 11 with the front legs of the derrick as illustrated in Figs. 1 and 2. The members 21 and 22 are interconnected out of the path of the traveling block by a tie member 23 extending in parallel relation with the rear girts. The brace members 21 and 22 are also connected adjacent the ends of the member 23 by members 24 and 25 which connect with the rear legs of the derrick. It is thus obvious that the lateral stresses tending to bow the front legs outwardly are restricted by the horizontal truss structures and that a substantially rigid though light weight structure is provided.

The upper ends of the derrick legs mount channel members 26 and 27 that are secured at their ends to the upper ends of the legs 3—5 and 4—6 respectively so that they do not interfere with the open front face 28 of the derrick or with the operation of cables at the rear side of the derrick as later described. Mounted on the channel members 26 and 27 is a crown block frame 29 including side rails 30 and 31 connected at the ends by front and rear rails 32 and 33. The side rails 30 and 31 are of such length that

the front and rear portion of the frame overhangs the front and rear sides of the derrick as indicated at 34 and 34'.

The crown block frame also includes a transverse rail member 35 that is spaced from the front rail member 32 to provide a pulley or sheave pocket 36 therebetween. The frame also includes rails 37 and 38 which extend parallel with the side rails 30 and 31 and connect the rear rail 33 with the transverse rail 35 to provide laterally spaced pockets 39, 40 and 41.

Rotatably journalled in suitable bearings carried by the rails 32 and 35 is a pulley or sheave 42 which rotates in a transverse plane offset forwardly from the front face of the derrick as best shown in Fig. 3. Similarly mounted in the pockets 39 and 41 are similar pulleys or sheaves 43 and 44 which rotate on an axis transverse to the axis of the pulley 42 and are spaced therefrom so that grooves 45 in the respective pulleys are disposed in a predetermined relation with an upward extension of the center line of the hole being drilled, that is, the vertical runs 46, 47, 48 and 49 of a tackle cable 50 when positioned in the grooves of the pulleys are equally spaced from the extended axis of the borehole so that the traveling block operates directly over the borehole and the load is equally distributed on the respective runs of the cable. In order that the runs of the cable may be substantially perpendicular, the pulleys (not shown) of the traveling block 19 are of a diameter corresponding to the diameter of the pulley 42 and the spacing between the pulleys 43 and 44. The traveling block pulleys are also spaced corresponding to the spacing of the pulleys in the crown block. With this arrangement a substantially wide spacing is maintained on the runs of the cable to eliminate twisting of the lines. The arrangement of pulleys also permits a substantially equal load on the derrick legs since the downruns 51 and 52 of the cable which depend from the pulleys 43 and 44 are in substantially conforming relation with the downruns operating over the transverse pulley 42. This arrangement of the pulleys also permits location of the sand pulley 54 within the pocket 40 so that the downrun of the sandline 55 is directly over the center of the borehole to also provide a straight pull on the line and substantially equal distribution of the load on the respective legs. The crown block frame may be attached to the channel members in any suitable manner.

In the illustrated instance the side rails 29 and 30 of the crown block frame are provided with laterally extending lugs 56 which seat upon the webs of the channels 26 and 27 and are secured thereto by fastening devices such as bolts 57.

In order to enclose the pulleys, the crown block is provided with a cover 58 having a plate portion 59 secured to the front rail 32 by a hinge 60. The plate 59 is provided with openings registering with the respective pulleys and the openings are covered by arcuate-shaped housings 61 which extend over the respective pulleys and are welded to the plate 59 to form integral parts of the cover. In order to secure the cover in position, the side rails 30 and 31 are provided with spring latches 62 that engage keepers 63 mounted on the sides of the housings that cover the pulleys 43 and 44.

Owing to the fact that the top of the derrick is relatively narrow, substantially all of the space is required to accommodate the traveling block and it is difficult to accommodate a tie truss 20 between the girts at the upper ends of the derrick.

In order to overcome this difficulty, the platform 64 of the "crow's nest" 65 cooperates with the girts in reinforcing and tying the legs of the derrick. The platform 64 is shown as including members 66 and 67 which diverge outwardly and rearwardly from the front legs and curve inwardly around the rear legs in spaced relation therewith as indicated at 68 and 69 so as to provide ample footing space at the corners of the derrick. The curved portions 68 and 69 are interconnected by a transverse member 70 that extends crosswise of the rear legs of the derrick in rearwardly spaced relation with the upper girt 11. The ends of the curved portions of the members 66 and 67 terminate short of the path of the downruns 51 and 52 of the tackle cable and are interconnected with the transverse member 70 by tie members 72 and 73 to cooperate in framing a notch-like opening in the platform to pass the cables as shown in Fig. 2. The platform members just disclosed carry a suitable flooring 74 preferably of a non-skid type and which cooperates therewith in providing a rigid truss-like structure externally of the derrick to tie in the legs and take the stresses that would normally be applied between the front legs of the derrick. The "crow's nest" also includes hand or guard rails 75 and 76 located over the curved portions of the platform. The hand rails are also preferably formed of tubular material and have portions 77 that extend laterally outwardly from the front legs to connect with slightly diverging rearwardly extending portions 78 that connect on rounding curves or transverse rear portions 79. The portions 79 are connected on rounding curves with rail portions 80 that connect with the gear legs on the respective sides of the opening in the platform through which the cables operate. The rails 75 and 76 are connected with the platform by struts 81 which are arranged to cooperate with the platform structure in enhancing the rigidity thereof. When the derrick is raised to an erect position on the derrick platform, it may be suitably guyed to further enhance the stability thereof under heavy loads.

In operating the tackle to raise and lower the traveling block as when raising or lowering the drilling string (not shown), the runs of the cable are substantially parallel and disposed, by reason of the location of the pulleys, so that the load is substantially uniformly applied to the respective legs of the derrick. It is also obvious that the "crow's nest" structure provides for stability of the relatively compact upper portion of the derrick and provides a truss structure corresponding to the trussing of the lower girts and which at the same time adequately forms the functions of a crow's nest during drilling operations. The rollers 18 which form a part of the derrick supporting bracket provide guides for the jerk and cat lines and also reinforce the bracket structure.

From the foregoing it is obvious that I have provided a derrick structure which is of strong, light-weight construction and that the pulley arrangement provides for substantially equal loading of the derrick legs.

What I claim and desire to secure by Letters Patent is:

1. A derrick including spaced corner legs, girts interconnecting the legs at the side and rear of the derrick to leave an open front side in which tackle is adapted to operate, platform members diverging outwardly and rearwardly from the front legs and curving inwardly around the rear

legs in spaced relation therewith, a transverse member extending parallel with a girt connecting the rear legs and extending beyond said sides of the derrick to connect said curved portions of said members, tie members connecting terminals of the curved portions with the transverse member, and a floor carried by said members and having an opening between said tie members to pass lines of said tackle.

2. A derrick including spaced corner legs, girts interconnecting the legs at the side and rear of the derrick to leave an open front side in which tackle is adapted to operate, platform members diverging outwardly and rearwardly from the front legs and curving rearwardly and inwardly around the rear legs in spaced relation therewith, a transverse member extending parallel with the girt connecting the rear legs and extending beyond said sides of the derrick to connect said curved portions of said members, tie members connecting terminals of the curved portions with the transverse member, a floor connecting side and rear girts with said diverging members, railings carried by said legs and projecting from the sides of the derrick over the platform, and braces connected with said diverging member at ends of the transverse member and diverging upwardly to connect with said rails.

3. A derrick including spaced corner legs, girts interconnecting the legs at the side and rear of the derrick to leave an open front side in which tackle is adapted to operate, platform members diverging outwardly and rearwardly from the front legs and curving rearwardly and inwardly around the rear legs in spaced relation therewith with ends terminating in spaced relation, a transverse member extending parallel with the girt connecting the rear legs and extending beyond said sides of the derrick to connect said curved portions of said members, tie members connecting said terminals of the curved portions with the transverse member to provide an opening therebetween for passage of lines from parts of said tackle, a floor carried by said members, railings carried by said legs and projecting from the sides of the derrick over the platform, a crown block frame carried on upper ends of the legs and having portions overhanging the open front and said opening at the rear side of the derrick, and pulleys carried by the crown block frame and positioned between the derrick legs within said overhanging portions to pass said tackle lines.

4. A derrick including corner legs, girts and sway braces connecting the legs at the sides and rear of the derrick, said legs being unconnected at the front side to provide an open faced derrick, a crown block frame carried on said legs and having a portion overhanging the front side of the derrick, a transverse pulley journaled in front of said frame and within said overhang at the open face side of the derrick, laterally spaced pulleys journaled in the frame in parallel relation with the sides of the derrick, said pulleys having cable grooves with the cable grooves in the spaced pulleys spaced from the groove in the transverse pulley in accordance with the diameter of the transverse pulley, whereby cables operating over the pulleys are equally spaced apart, and a sand pulley carried by the crown block frame intermediate the spaced pulleys and positioned tangentially of the axis of the hole to be drilled.

5. A derrick including corner legs, girts and sway braces connecting the legs at the sides and

rear of the derrick, said legs being unconnected at the front side to provide an open faced derrick, a crown block frame carried on said legs and having portions overhanging front and rear sides of the derrick, a transverse pulley located in the overhang at the open face side of the derrick, laterally spaced pulleys positioned in the frame in parallel relation with the sides of the derrick, said pulleys having cable grooves with the cable grooves in the spaced pulleys spaced from the groove in the transverse pulley in accordance with the diameter of the transverse pulley whereby cables operating over the pulleys are substantially equally spaced apart, and a sand pulley carried by the crown block frame intermediate the spaced pulleys and positioned tangentially of the axis of the hole to be drilled.

6. A derrick including corner legs, girts, and sway braces connecting the legs at the sides and rear of the derrick, said legs being unconnected at the front side to provide an open faced derrick, a crown block frame carried on said legs and having a front portion overhanging the front open face of the derrick and a rear portion overhanging the rear side of the derrick, a transverse pulley journaled in front of said frame and within said overhang at the open face side of the derrick, laterally spaced pulleys journaled in the frame in parallel relation with sides of the derrick and having portions operating in the rear overhang of the crown block frame, said pulleys having cable grooves, with the cable grooves in the spaced pulleys spaced from the grooves in the transverse pulley whereby cables operating over the pulleys are equally spaced apart.

7. A derrick adapted for support over a bore hole and including corner legs, girts and sway braces connecting the legs at the sides and rear of the derrick, said legs being unconnected at the front side to provide an open faced derrick, a crown block frame carried on said legs and having portions overhanging front and rear sides of the derrick, a transverse pulley located completely within the overhang at the front side and operating in a plane parallel with the front of the derrick, and laterally spaced pulleys positioned within the frame in parallel relation with the sides of the derrick, said pulleys having cable grooves with the cable grooves in the spaced pulleys spaced from the groove in the transverse pulley and the spaced pulleys being spaced apart in accordance with the diameter of the transverse pulley, said pulleys being arranged with the adjacent portions of the grooves of the respective pulleys at the horizontal diameter thereof located substantially equal distances apart whereby cables operating over the pulleys are equally spaced apart in directions parallel with the transverse pulley.
